UNITED STATES PATENT OFFICE.

THOMAS O. PERRY, OF CHICAGO, ILLINOIS.

AIR-COMPRESSOR.

No. 927,162.

Specification of Letters Patent.

Patented July 6, 1909.

Application filed September 9, 1907. Serial No. 392,063.

To all whom it may concern:

Be it known that I, THOMAS O. PERRY, a citizen of the United States, residing at Chicago, in the county of Cook and State of Illinois, have invented new and useful Improvements in Air-Compressors, of which the following is a specification.

This invention relates to improvements in the packing of plungers for air compressors and pumps.

The main object of my invention is to provide an elastic plunger packing which will not leak on account of wear, and which will cause as little friction as possible.

These objects I attain by the mechanism illustrated in the accompanying drawings, in which—

Figure 1 is an exterior side view of the air compressor and its supports in elevation; Fig. 2 is an exterior front view of the air compressor and its supports in elevation; Fig. 3 is a plan of the cap or head to the cylinder of the air compressor; Fig. 4 is a sectional elevation of the air compressor in a plane indicated by the broken lines 4-4 on Figs. 3 and 5; Fig. 5 is a plan of the plunger packing and accessories showing the plunger in section; and Fig. 6 is an enlarged plan of the plunger packing and accessories showing the plunger in section.

Similar letters refer to similar parts throughout the several views.

The compressor cylinder E has exterior flanges both at its upper and lower ends. The cap C, is secured to the upper end of the cylinder by screws entering the upper flange. Plunger, F, fits the interior of cylinder, E, loosely, is closed at its upper end, protrudes from the lower end of the cylinder and carries at its lower extremity a cross-head, G. Plunger rods, G², rigidly connect the cross-head with the drive-head, G', which is adapted to reciprocate above the cap C, and is centrally connected to the actuating rod, r. A supporting plate, A', is secured to the lower end of the pipe A, which is supposed to be fixed above in connection with some form of motor adapted to actuate the rod, r. Supporting guide rods, C², pass loosely through the drive head and rigidly connect the cylinder cap, C, to the supporting plate, A'.

Surrounding the plunger and drawn to the lower cylinder flange by screws is a clamping ring, N, having an interior flange underneath loosely fitting the plunger, and inclosing together with the cylinder end an annular

packing space. An elastic cylindrical packing, Q, having an exterior flange on its under side in close contact with the clamping ring surrounds and presses against the plunger 60 within the annular space, which is thus tightly closed, communicating only with the interior of the cylinder. A packing ring, n, is interposed between the cylinder end and exterior flange of the packing so that it binds 65 the packing flange by tightening the clamping screw. Between the upper portions of the packing, Q, and packing ring, n, is a thin annular recess, adapted to receive packing springs, q, which react between the packing 70 ring and the elastic packing. These packing springs are preferably arranged in two annular layers, one within the other, and each layer is made up of several thin, flat spring sections. Four spring sections are shown 75 in each layer in Figs. 5 and 6. The spring sections are all under tension. In the outer layer the ends of the spring sections press outward against the packing ring, while their centers press inward against the 80 ends of the spring sections in the inner layer, which in turn press against the elastic packing throughout their length by reason of their proper form before insertion and the superior stiffness of the outer spring 85 sections. These spring sections may all be nearly straight before being sprung into the annular recess, or they may be curved before insertion as suits best the tensions required when in place. The packing may be made 90 of leather or other yielding material. The upper side of the clamping ring, N, fits closely around an annular shoulder on the end of the cylinder of about the same external diameter as the packing ring, n. The annular packing space is also adapted to receive 95 other forms of packing such as are ordinarily used.

The cross-head, G, is not rigidly connected to the plunger, F, but is merely guided 100 loosely in its open lower end and is carried rigidly by a tie rod, L', whose upper end connects with a safety valve, L, which seats against and is guided in the upper closed head of the plunger. A powerful safety spring, M, 105 surrounding the tie rod, reacts between the closed head of the plunger and the cross head so as to hold the safety valve closed. The safety spring should have sufficient tension to drive the plunger, without yielding, 110 against any normal resistance, but is designed to yield to abnormal resistance, such

as might result from accidental clogging of the outlet or undue compression of air, so as to relieve the excessive pressure by letting the safety valve open. A very slight lifting of the safety valve lets compressed air pass sufficiently to avoid dangerous pressure.

In the cylinder head is a check valve, J, opening outward, covered by a cap, O', from which the outlet or delivery pipe, O, rises. The intake valve, H, opens inward and is carried by and rests against a hollow cage, C', which screws into the cylinder head to one side of the outlet. The guiding stem of the intake valve reaches up through the center of the cage and terminates in a knob, H', attached so as to form a shoulder beneath which a helical spring, H'', coiled around the stem and resting in a recess of the cage reacts to balance the weight of the valve more or less. The under side of the knob, H', is guided in the recess and its upper part is enlarged so as to limit the vertical movement of the intake valve. Around the periphery of the cage are openings for the passage of air.

It should be noticed that the air pressure within the cylinder having access past the plunger to the annular packing space acts to press the packing against the plunger as well as against the clamping ring, and this air pressure may suffice to make the packing sufficiently tight without the aid of the packing springs or the packing ring after compression begins. But without the packing springs to close the packing tightly against the plunger before commencement of the compression stroke, too much air might escape for want of initial tension. The combined pressure of the packing springs and compressed air against the packing would cause considerable friction, if the pull on the packing due to friction did not help to relieve the pressure against the plunger by reason of the pull of the plunger being directed away from the clamped exterior flange of the elastic packing during the compressing stroke. Furthermore, the air pressure against the packing is materially reduced by reason of the very limited annular space between the plunger and the cylinder through which the air must pass to reach the annular packing space. These considerations render waste of applied actuating energy due to plunger friction much less with this form of packing than with ordinary piston packings made of cup-shaped leather.

What I claim as my invention, and desire to secure by Letters Patent, is—

1. In an air compressor, the combination with a plunger and a cylinder having closed and open ends, of an annular inclosure at the open end of the cylinder surrounding the

plunger, a flexible annular packing closely surrounding said plunger within said inclosure, and springs adapted to react between the outer wall of said inclosure and said flexible packing, said springs being arranged in two annular concentric layers so that the outer layer of springs presses the inner layer evenly against all the sides of the packing, substantially as herein set forth. 65

2. In an air compressor, the combination with a plunger and a cylinder having open and closed ends, of a flexible annular packing closely surrounding the plunger at the open end of the cylinder, and having an exterior packing flange, a packing ring interposed between the packing flange and the open end of the cylinder, a clamping ring adapted to clamp the packing flange against the packing ring, and springs interposed and reacting between the packing ring and flexible packing so as to press the packing evenly against the plunger all around its exterior, substantially as herein set forth. 75

3. In an air compressor, the combination with the plunger, and cylinder having open and closed ends, of a clamping ring adapted to close against the open end of said cylinder forming therewith around the plunger an annular packing space, a flexible annular packing within said packing space adapted to press tightly around said plunger and against said clamping ring, and packing springs within said annular space adapted to press said flexible packing inward against said plunger on all sides, said annular packing space being adapted to receive and hold compressed air from the interior of the cylinder, substantially as herein set forth. 90

4. In an air compressor, the combination with the plunger, and cylinder having open and closed ends, of a clamping ring adapted to close against the open end of said cylinder forming therewith around the plunger an annular packing space, a flexible annular packing within said packing space adapted to press tightly around said plunger and against said clamping ring, a packing ring within said packing space outside of said flexible packing, and springs reacting between said packing ring and said flexible packing adapted to press the latter inward against the plunger on all sides, said annular packing space being adapted to receive and hold compressed air from the interior of the cylinder, substantially as herein set forth. 105

In testimony whereof I have signed my name to this specification in the presence of two subscribing witnesses.

THOMAS O. PERRY.
